SUBMERSIBLE WATERCRAFT

Robert J. Lang, 18400 Malden St.,
Northridge, Calif. 91324

Filed Aug. 21, 1967, Ser. No. 8,329

Term of patent 14 years

(Cl. D71—1)

FIGURE 1 is a top plan view of a submersible watercraft showing my new design;

FIG. 2 is a side elevational view thereof;

FIG. 3 is a rear elevational view thereof; and

FIG. 4 is a front elevational view thereof.

I claim:

The ornamental design for a submersible watercraft, substantially as shown.
